SAFETY LIFTING JACK.

1,417,254.

Specification of Letters Patent. Patented May 23, 1922.

Application filed May 10, 1921. Serial No. 468,301.

To all whom it may concern:

Be it known that I, DAVID C. KLAUSMEYER, a citizen of the United States, and residing at Cincinnati, in the county of Hamilton and State of Ohio, have invented a new and Improved Safety Lifting Jack, of which the following specification is a full disclosure.

This invention relates to lifting jacks and has more special reference to a lifting jack characterized by the provision of safety means for avoiding accident through the collapse of the jack due to the failure of the usual load sustaining parts. These load sustaining parts, in the specific embodiment illustrated, take the form of the conventional screw and nut. A stripping of the threads of the screw and nut may result when a load exceeding the sustaining capacity of the threads is applied to the jack. When the parts are new, the danger of collapse of the jack is comparatively remote because ordinarily the applied load will be well within the designed capacity of the jack. After the jack has been in use for some time, however, the threads of the nut and screw may become worn to such an extent that the jack may collapse even if a load considerably less than the designed capacity is applied.

An object of this invention is to guard against the possibility of collapse and is accomplished by providing an auxiliary member which does not function in the ordinary operation of the jack, thereby obviating its thread wear, so that the load may be carried by its unused and unworn threads; if the threads, which ordinarily serve to sustain the load, fail.

The drawing exemplifies the essentials of the invention.

Fig. 1 is a general view of the jack mechanism.

Figure 2 is a sectional view on a central vertical plane through Fig. 1.

Fig. 3 is a sectional view on the line 3—3 of Fig. 2.

In said drawing the part A indicates the base of the lifting jack. While the particular shape of this base forms no part of the invention, nevertheless it is characterized by the provision of a vertical opening A', having a restricted portion A'' to afford a ledge or abutment on which the movable

parts of the jack are temporarily sustained, 55 in the event of the failure of the load sustaining parts. A nut B is held against rotation in this vertical opening A' by a set screw B', and rests on a shouldered portion of the base A, although this special 60 support for the nut B is of course not absolutely essential, since it may be adequately supported by increasing the size of the set screws. Furthermore the nut B might be cast integral with the base A and the invention 65 contemplates such construction as within its intended scope. Irrespective of whether the nut is cast with the base or is a separate entity, a vertical screw C is in threaded engagement with it and serves to 70 move the object to be raised relatively to the base A. The upper end of this vertical screw terminates in a stub shaft having an annular groove C', the latter being engaged by the end of a screw D which passes 75 through a bearing member D'. The member D' preferably has its upper face corrugated in the manner illustrated to afford a non slip surface to support the work. While the preferred constructional form utilizes a bearing member D' as indicated, nevertheless, it is to be understood that the end 80 of the screw might under certain circumstances directly engage the object to be lifted; or the preferred construction illustrated 85 in the drawing, might be further modified by providing ball bearings to reduce the friction between the bearing member D' and the end of the vertical shaft to a minimum. Inasmuch as the relative movement 90 of the bearing plate D' and the base A is accomplished by the rotation of the screw C and its consequent translation with respect to nut B effected an organization for rotating the screw is essential. The screw 95 C may be conveniently rotated by the construction shown in the drawings, in which a capstan head E, having a plurality of openings E' each of which is adapted to receive a capstan bar may be manually rotated. This capstan head is secured to the screw in any convenient manner, as for example, by tapping an opening in the screw and in the capstan head and driving a pin or threading a screw into this opening. 100 While the screw C may be manually driven in the manner just indicated, nevertheless it is to be understood that a power drive,

might be utilized, for example, by splining a worm wheel to an extension shaft secured to the lower end of the screw C.

In order to prevent the screw C from dropping down through the nut B, due to the stripping of the threads, an auxiliary safety collar or nut F is threaded on the screw C and is so proportioned as to support this screw, in case the aforesaid stripping of the threads occurs. The collar F has a connecting part adapted to cooperate with the nut B which preferably takes the form of an upstanding tongue F' adapted to engage a slot G in the nut B when the parts are in normal position, that is, when the threads of the nut B and the screw C are meshing properly. The preservation of the threads of the auxiliary collar is accomplished by slightly spacing the collar from the nut B, so that it rides idly on the screw C, and, due to the connection indicated, is held stationary by the nut B, without, in any way, partaking in the support of the load. So long as the threads of the nut B are properly functioning with the threads of the screw C; the collar F, through its connection with the nut B, maintains the initial spaced relative position with respect thereto. If, however, due to a stripping of the threads, the screw C moves downwardly through the nut B, the auxiliary safety nut F will become separated from the nut B and the connecting tongue disengaged from its socket. If the rotation of the screw C is continued after this disengagement occurs as may well be the case, the auxiliary safety nut F will rotate with the screw C preferably riding on the ball bearing cage G' of the ball bearings H, which are carried on the shouldered portion A'' of the base A. Evidently the nut F might ride directly on ball bearings which ride only in a lower race. Irrespective of the manner in which the drop of the safety nut is stopped, it is desirable to make the fall as small as possible, and to this end the abutment or ledge is located as near to the nut B as possible and yet sufficiently spaced so as to permit disengagement of the tongue from the socket. In this connection it is to be observed that the tongue may be comparatively short inasmuch as but little shear must be resisted. Inasmuch as the threads of the auxiliary nut are unworn and inasmuch as it freely rotates with the screw C, it will temporarily sustain a comparatively heavy load, even though the usual load sustaining threads of the screw C, are entirely stripped. Evidently the length of the collar F may be increased in proportion to the length of the threaded part of the nut, so that the collar will be capable of supporting any desired weight and any degree of safety may be afforded within certain limits, as will be readily understood.

Having thus revealed the invention, I claim as new and desire to secure the following combinations of elements, or equivalents thereof, by Letters Patent of the United States:

1. A lifting jack of the nature disclosed combining a screw and a pair of elements cooperating therewith, one of which normally sustains the load and the other of which is adapted to sustain the load on the failure of the other element of said pair.
2. A lifting jack of the nature disclosed combining a pair of cooperating relatively rotatable load sustaining elements and a safety member adapted to idly cooperate with one of said members when said load sustaining elements are working normally and adapted to sustain the load on the failure of the load sustaining elements.
3. A lifting jack of the nature disclosed combining a rotatable screw; a stationary part in threaded engagement with said screw; and a member slightly spaced from said threaded part held stationary thereby and adapted to receive the thrust thereof in the event of the failure of the nut.
4. A lifting jack combining two separable members, one of which constitutes the base; a screw cooperating with these members; and a stationary safety collar in threaded engagement with said screw and having a connection for holding it relatively stationary to a portion of the base, said connection being separable during any untoward translation of said screw, the safety collar being adapted to arrest further translation of the screw by abutting against a portion of the base.
5. A lifting jack comprising two members one of which constitutes the base and the other the carrier of the object; a nut secured to the one constituting the base and a screw journaled to the other; a safety collar threaded on said screw in proximity with said nut and positioned adjacent an abutment in the base, and a detachable connection between the collar and nut adapted normally to cause the collar to remain stationary.
6. A safety lifting-jack combining a stationary member in the nature of a base and a member adapted to be raised relatively thereto; a nut journaled in one of said members and normally restrained against rotation relatively thereto; a screw rotatably secured to the other member and threaded through said journaled nut; and means operative under abnormal conditions to release said restraint and enable said journaled nut to rotate as a unit with said screw whereby the raised member may be supported but not further elevated by said journaled nut notwithstanding a continued rotation of said screw.
7. A safety lifting-jack combining an elevatable member and a stationary base; a

screw rotatably secured to the elevatable member; a nut rotatively seated in the base; means non-rotatably related to said base normally operative on said nut to prohibit its 5 rotation, said means being adapted under abnormal conditions to permit said nut to rotate as a unit with said screw; and a ball-bearing underlying said nut and adapted to receive the downward thrust between said 10 nut and the base so as to promote the rotation of said nut when permitted by said non-rotatable means.

8. A safety lifting-jack combining a stationary base and an elevatable member; a 15 nut seated in an upright socket in said base; an anti-friction thrust-bearing interposed between said nut and a shoulder at the lower end of said socket; a tubular element arranged concentrically with the nut and non- 20 rotatably connected to said base and normally engaging said nut to prevent rotation thereof, said nut and element being adapted to become disengaged under abnormal conditions to permit said nut to rotate freely; and 25 a lifting-screw rotatably connected to the elevatable member and threaded through said nut.

9. A safety lifting-jack combining a socketed base providing an annular seat; an annular anti-friction thrust-bearing resting on said seat; a tubular element non-rotatably secured to said base and providing a clutch-like portion spaced from said thrust bearing; a nut intervening between said thrust-bearing 35 and said element and having its upper end formed clutch-like and normally clutched to said element so as to be prevented thereby from rotating; an elevatable cap; and a screw having its upper end rotatably

secured to said cap and extending successively through the bores of said element, said nut and said thrust-bearing and adapted to cooperate with said parts to effect a shift of one of said clutch-like parts, the construction being such that under abnormal 45 conditions said element and said nut will become de-clutched to permit said nut to rotate as a unit with said screw while resting on said anti-friction thrust-bearing and thereby render the screw impotent to effect 50 a further elevation of said cap.

10. A safety lifting-jack combining a base having a socket; an anti-friction thrust-bearing shouldered against the lower end of said socket, a first tubular part non-rotatably secured to said member; a second tubular part located in said socket and having its lower end adjacent said thrust-bearing and having its upper end engaging said first part so as to be held thereby against rotation, one 60 of said parts being adapted under abnormal conditions to shift axially sufficiently to disengage the other part and permit the second part to rotate; and a rotatably mounted lifting-screw threaded through said second 65 part and adapted to effect a rotation thereof while being supported by said anti-friction bearing when said second part is disconnected from said first part and thereby render said rotating lifting-screw impotent to 70 feed through said second part.

In witness whereof, I hereunto subscribe my name, as attested by the two subscribing witnesses.

DAVID C. KLAUSMEYER.
